FIG. 2

Portions of the elements shown in dotted lines in FIG. 1 have been omitted from the remaining views for clarity of illustration. The dominant features of my design reside in the portions illustrated in solid lines.

I claim:

The ornamental design for an industrial tractor, as shown and described.
